James Blake Inventor

United States Patent Office.

JAMES BLAKE, OF SCRANTON, PENNSYLVANIA, ASSIGNOR TO HIMSELF
AND GEORGE BLAKE, OF SAME PLACE.

Letters Patent No. 106,110, dated August 9, 1870.

IMPROVED SUPPORT FOR TABLES.

The Schedule referred to in these Letters Patent and making part of the same.

I, JAMES BLAKE, of the city of Scranton, county of Luzerne and State of Pennsylvania, have invented certain Improvements in Auxiliary Tables or Supports, of which the following is a specification.

Nature and Object of my Invention.

My invention relates to the manner of securing auxiliary tables, adjustable platforms, or other supports to tables, sewing-machine stands, desks, shelves, &c., the object of my invention being to secure the auxiliary table, platform, or support, to the main table, shelf, &c., firmly and effectually, but easily, by means which will permit ready and easy detachment.

One form of my invention is shown in the drawing and specification of a patent granted to me, and dated March 23, 1869, numbered 88,121, and reissued November 2, 1869, to JAMES and GEORGE BLAKE, assignees of JAMES BLAKE, and numbered 3,697, wherein it is represented as a part of the "supporting or attaching bracket, arm, hinge, or hanger D."

Description of Accompanying Drawing.

Figure 5 is a side elevation of the "bracket D" above referred to.

Figure 6 is a side elevation of a modification of fig. 5, level with the main table.

Figure 6 $\frac{1}{2}$ is a side elevation of still another modification, in which the two tables are on level and the stop function is performed by another pin, p, above the pin a, engaging a similar recess.

Figure 7 is a side elevation of another form, with the beak C resting under the edge of the table.

General Description.

In fig. 5 the auxiliary support is held in place, or secured when put in place, by the combined action of the beak C, recess d, pin a, and the mere weight of the auxiliary table or support resting upon the beak C, as a fulcrum, the effect of which is to clamp the parts together, so as to prevent lateral or end motion.

In fig. 6 the beak C, projection p, and weight of the auxiliary, secure the same method of action and the same result by substantially the same arrangement.

In fig. 6 $\frac{1}{2}$ the beak function is performed as in fig. 6, but instead of the point or projection p, the pin p,

similar in all respects to the pin a, takes in a recess of the upper bar of the slot b precisely like the recess d, in fig. 5, &c.

This stop may vary in form and location, as in figs. 5, 6, 6 $\frac{1}{2}$, and even fig. 7, where the hook h acts as the stop, without substantial variation from my invention.

In fig. 7 there is no stop action at the end of the bracket, and no recess or projection, but the beak C, being formed in a hook-shape, itself performs both the supporting and securing functions of the beak and the recess d, pin a, or projection p.

I do not intend, by anything herein, to confine myself to the special form or location of the stop or beak details. Varying in form the stop may be moved from the position of the original recess d and pin a toward the beak, and at any point operate effectually and similarly. It may even be revolved around the beak, as in fig. 7, becoming, when so revolved a hook, h.

The hook h, manifestly, could be moved toward the further end of the bracket on its under side. But in all these variations the essential feature in accomplishing the object of my invention is the co-operation of the beak with the stop in such a manner as to secure the auxiliary to the main table, under all the treatment it is likely to receive, except the one action of lifting the auxiliary, and thereafter drawing the same from the main table, when it may be dropped and hang under the table. This peculiar joint action of the beak and stop may be styled co-operation or co-ordination, which constitutes the principle of this my invention. So the beak may, by change in its shape simply, perform both the functions of beak and stop in co-ordination.

Claim.

I claim as my invention—

An auxiliary table, provided with one or more beaks and one or more stops co-ordinated, for the purpose of securing it in position, substantially as described and shown.

JAMES BLAKE.
